UNITED STATES PATENT OFFICE.

WALTER E. POWELL, DECEASED, BY ROSA E. POWELL, ADMINISTRATRIX, OF WICHITA FALLS, TEXAS, ASSIGNOR OF ONE-HALF TO CARRIE WARDRIP, OF WICHITA FALLS, TEXAS.

HAY-PRESS.

1,358,109.

Specification of Letters Patent.

Patented Nov. 9, 1920.

Application filed May 24, 1919. Serial No. 299,648.

To all whom it may concern:

Be it known that WALTER E. POWELL, deceased, late a citizen of the United States, had prior to his death invented certain new 5 and useful Improvements in Hay-Presses, of which the following is a specification.

This invention relates to hay presses and more particularly to a hay press especially designed to be used for forming bales which 10 will be tightly compressed.

One of the objects of the invention is to provide a hand or power operated hay press which may be operated to cause a great pressure to be exerted on the hay or other material being pressed, with a minimum exertion on the power means.

A further object of this invention is to provide a device of this character which consists of comparatively few parts and is simple in construction, but durable and well adapted to withstand the rough usage to which devices of this character are ordinarily subjected.

For a full description of the invention 25 and the advantages and merits thereof, reference is to be had to the following description and accompanying drawings.

Figure 1 is a side elevation of the device constructed in accordance with the invention.

Fig. 2 is a plan view of the same.

Fig. 3 is a longitudinal section taken on the line 3—3 of Fig. 2.

Fig. 4 is a front elevation, and

Fig. 5 is a rear end elevation.

Referring to the drawings, wherein like characters of reference indicate like or corresponding parts throughout the several views, the wheels 1 support the body 2 which may be of any preferred construction and, in the present instance, consists of the longitudinal beam 3 supported on a bolster 4 supported by the rear axle. This beam 3 extends considerably beyond the rear wheels and forms the bottom of the baling chamber 5. The latter is provided with side walls 6 and a top wall 7 whereby a longitudinal substantially rectangular compartment is provided for receiving the material to form the bale. One end of the top wall 7 is provided with an opening 8 and at this point a hopper 9 is formed whereby the hay or other material may be fed into the baling chamber.

Mounted for sliding movement on the

bar 2 is a reciprocating piston 10 which carries a compressor head 11 at one end and is provided at its other end with an elongated depression 12 fitting over a longitudinal tongue 13 carried by the bar 2. 60 The member 13 being disposed in the recess 12, will longitudinally guide the member 10 when it is reciprocated on the bar 2.

The front wheels support the front axle 14 and the latter has connected thereto in any preferred manner the tongue 15 to which the draft animals are harnessed. Projecting upwardly through the front axle 14 is a king pin 16 which receives the complementary circular plates 17 the latter 70 being interposed between the front axle 14 and the surface of the beam 3. The upper extended end of the king pin 16 is equipped with a sleeve 18 to which is attached the rocker member 19, having oppositely extending portions which are equipped at their terminals with the rollers 20. Mounted above the member 19 is a spool or collar 21 encircling which is a ring 22 connected to a rod 23 which latter is joined 80 to a yoke member 24. The parallel arms of the yoke member are extended through guide members 25 which are mounted in the beam 3. The terminals of the parallel arms of the yoke member are secured in the 85 beam on opposite sides of the reciprocating bar 10.

The upper extended end of the sleeve 18 has connected thereto, an operating arm 26, one end of which is joined to an operating 90 lever 27 while the opposite end of the arm 26 is connected to a brace rod 28 which is also joined to one end of the lever 27 as shown in Fig. 2. The lever 27 receives the power which turns the arm for actuating 95 the mechanism. As shown in Fig. 2, the reciprocating bar 10 is provided at one side with an offset portion 29 which forms a shoulder 30 and also carries a link 31 which connects an actuating bar 32 with the reciprocating bar 10. One end of the bar 32 is provided with a wearing plate 33 and the end is curved as shown to form the rounded corner 34 and the depression or hollow surface 35 against which the rollers 20 operate. 100 A retaining link 36 is connected to the bar 32 near one end thereof and the opposite end of the link is joined by a pivot to the plate 17. This link serves to maintain the member 32 in position during its longitudi- 105 110

nal movement. A coil contraction spring 37 has one end fixed, as indicated at 38, to the beam 2 and its opposite end is joined to the reciprocating bar 10. This spring tends to draw the plunger member outwardly to the position shown in Fig. 3.

Within the hopper, below the opening 8, are the retaining members 39 which tend to maintain a quantity of hay in position 10 to be compressed by the plunger element 11 and these members include the inwardly projecting flanges 40 and the exterior springs 41, attached to the exteriors of the walls 6 and engaging the members 40 to 15 urge them inwardly. The members 40 are pivoted to the walls of the baling chamber as shown so that they are forced inwardly by the spring member 41.

To prevent the hay being deposited from 20 the hopper into the end of the baling chamber when the piston 11 is thrust forwardly, I have provided a stopping device which closes the opening 8 when the plunger or compression member 11 is thrust inwardly. 25 Attached to the upper edge of the compression plate 11 is a horizontal plate 44 the edge of which is hingedly connected as indicated at 45, to a longer plate 46. Parallel guide members forming guide ways 47 are 30 arranged on the rear end of the hopper and the rear or upper edge of the plate 46 carries a rod 48 which has its ends extended to form pinions 49 which are received in the 35 guide ways 47. When the plunger element 11 is thrust forwardly the plate 46 being hingedly connected to the plate 44 will be drawn inwardly, the guide members 49 following in the guide ways 47 so that the 40 plates 44 and 46 will be disposed substantially horizontally when the plunger element 11 moves inwardly for its complete movement. When the plunger element is returned the guide members will tend to 45 return the members 49 in order that the plate 46 will be swung on its hinge 45 and projected substantially upwardly as indi-

cated in Fig. 3. Thus the opening 8 may be closed to prevent the material from dropping when the plunger is in its innermost position.

The foregoing description and accompanying drawings have reference to what might be considered to be the approved or preferred form of the invention. I desire it to be understood that such changes may be 5 made in construction, combination and arrangement of parts, materials, dimensions, et cetera, as may prove expedient and fall within the scope of the appended claim.

Having thus fully described my invention what I claim as new and desire to secure by Letters Patent, is:—

In a baling press, the combination of a wheel supported frame, and a compressor member including a reciprocating bar, an actuating arm mounted at the front of the frame for swinging movement and comprising oppositely extending portions having rollers mounted at their free terminals, a link attached to the said reciprocating bar, the latter having a shoulder adjacent the said link, an actuating member connected to the said link and adapted to abut against the said shoulder, the opposite end of the said actuating member also having a 75 link connected to the said frame to limit the swinging movement of the actuating member, a wearing plate formed on one end of the actuating member and equipped with a rounded portion, and a curved depression 80 adapted to engage the said rollers when the swinging member is actuated, and means for imparting movement to the said swinging member.

In testimony whereof I affix my signature. 85

Mrs. ROSA E. POWELL,
Administratrix of the estate of Walter E.
Powell, deceased.
